UNITED STATES PATENT OFFICE.

JOHN N. PHILBROOK, OF NEW YORK, N. Y., ASSIGNOR TO RAYMOND CONCRETE PILE COMPANY, OF NEW YORK, N. Y., A CORPORATION OF NEW JERSEY.

RETAINING-WALL.

1,099,664.

Specification of Letters Patent.

Patented June 9, 1914.

Application filed September 26, 1913. Serial No. 791,910.

To all whom it may concern:

Be it known that I, JOHN N. PHILBROOK, a citizen of the United States, residing at New York city, county of New York, and State of New York, have invented certain new and useful Improvements in Retaining-Walls, of which the following is a full, clear, and exact description.

This invention is an improvement in bulkheads or retaining walls, more especially those constructed along water fronts, or which under similar conditions of installation and use are subjected to great horizontal and vertical stresses, due to the weight of the fill behind the wall, or heavy loads supported thereon.

In a patent to Maxwell M. Upson, No. 981,822, dated January 17, 1911, a retaining wall structure is shown, one element of which comprises a series of piling units, each extending down into the earth bottom and arranged successively adjacent to each other in a row and longitudinally interlocking to constitute a tight sheet piling retaining wall, the individual piling units of which are relieved of horizontal loads by the co-operative action therewith of a horizontal beam maintained in position transversely along the top of the wall.

The invention of the patent referred to is, essentially, a reinforced concrete structure, both the piling units and the horizontal beam being composed of that material, and it has proved to be a construction of great practical value, being recognized among engineers as a standard type or form of construction for its intended purpose.

The invention upon which this application for patent is based, is an improvement upon that of the patent mentioned, the primary object of the present improvement being to secure the advantages and benefits of the said patented construction, but with a great saving of expense and of the time and labor involved in its installation.

The nature and purpose of my invention will be understood from a consideration of the fact that considerable difficulty is often encountered in the construction of such retaining walls, in getting a sufficiently solid bottom support for properly sustaining the vertical pressures, without driving the piling units to considerable depths, a proceeding which not only requires very long piles, but involves increased expense in their

manufacture and installation. To avoid this necessity, as also those objections which ordinarily attach to the use of unprotected wooden piles, I employ, in lieu of interlocking concrete piling units, a relatively smaller number of suitable piles, preferably of wood, in combination with sections of concrete surrounding the same and which are adapted to interlock and form a substantially tight or continuous wall. In this way the requisite strength in the retaining wall to withstand both horizontal and vertical loads is secured, while by covering wooden piles with the concrete sections and extending the latter down for a relatively short distance below the mud line, such piles are protected against the attacks of marine insects and indefinitely preserved.

The construction of my improved retaining wall and the manner of building the same, will be described in detail by reference to the accompanying drawings, in which—

Figure 1 is a general sectional view, partly in elevation, of a retaining wall embodying the invention. Fig. 2 is a top plan view of the same, and Fig. 3 is a sectional view of a pile with its surrounding protective concrete section.

All of the sections or units comprising the retaining wall, or such portions of the same as are below the water line, are formed in suitable molds and, preferably, of the same dimensions and materials. I make them each of the form of a slab A, integral with a body portion B, preferably on one side only of the slab, and through which, in those units designed to surround the piles, there is a circular opening of sufficient diameter to permit them to be threaded over the piles C.

The edges of the slabs A may be formed or provided with suitable means to enable them to interlock. For example, beaded plates or headed bolts D may be cast in one edge and corresponding grooves formed in the other, such grooves being preferably lined or faced with metal and obtained by casting in the slabs metallic plates E of proper conformation.

In constructing the retaining wall by the use of wooden piles, the latter are chosen of approximately the requisite length and driven at the proper intervals to permit the concrete sections to be threaded over them and to interlock with one another. By

washing out the mud, or otherwise, the said sections are carried down below the normal bottom to a distance sufficient to insure protection to the piles from the attacks of marine insects. The piles are cut off at the top slightly above the mean low water level so as to remain saturated at all times, and are surrounded to their top with the concrete sections.

10 Above the tops of the piles proper, such additional concrete sections F as may be used to build up the wall to the desired height, are or may be solid, and the wall is surmounted and finished by a horizontal 15 beam or superstructure G, constructed and applied in the manner set forth in the patent above referred to, or otherwise to secure the desired result.

The sections F may, if desired, be separately formed and applied to the pile-slabs A, or may be made integral with the beam or superstructure G, as shown in Fig. 1.

The concrete sections comprising the slabs and pile protectors, the solid sections used 25 above the piles, the horizontal superstructure and all other concrete parts employed in the structure are reinforced in the usual and proper manner, and all individual sections, molded or cast prior to their introduction 30 into this structure, may be locked or bonded together in the manner usual in such cases, to secure better alinement, greater rigidity and the strength necessary to withstand lateral stresses.

35 The structure may be strengthened by the addition of buttresses H, of any proper construction, but the details of such devices are not shown, as they may be of the usual character and they form in themselves no part 40 of my present improvement.

It is manifest that the specific form of the sectional concrete units which make up the retaining wall may be greatly varied without departing from the invention, and that 45 the special means for locking and interlocking the same are not material.

What I claim is:

1. A retaining wall comprising, in combi-

nation, a series of wooden piles, sections of concrete surrounding said piles, and interlocking one with another, and concrete members forming an extension of the wall above the water line. 50

2. An element for retaining walls, comprising a slab and a hollow cylinder and a wooden pile driven into the earth, said pile 55 projecting through said hollow cylinder.

3. A retaining wall comprising, in combination, a series of piles, sections of concrete surrounding said piles and interlocking one with another, and a horizontal beam along the upper portion of the wall adapted 60 to relieve the individual piles of horizontal load.

4. A retaining wall comprising, in combination, a series of wooden piles driven into the earth, a series of concrete sections each surrounding the portion of a wooden pile that projects between low water and the surface, each concrete section being extended 65 laterally to contact with adjacent sections so as to form therewith an integral concrete structure. 70

5. A retaining wall comprising, in combination, a series of wooden piles driven into the earth, a series of concrete sections substantially T-shape in cross section, each surrounding the portion of a wooden pile that projects between low water and the surface, each concrete section being extended laterally to contact with adjacent sections so as to form therewith an integral concrete structure. 75 80

6. A retaining wall comprising, in combination, a series of concrete members, each formed with a slab and a hollow cylinder and a series of wooden piles driven into the earth, each pile projecting through one of 85 said hollow cylinders.

In testimony whereof I affix my signature 90 in the presence of two subscribing witnesses.

JOHN N. PHILBROOK.
